UNITED STATES PATENT OFFICE.

JOHN WALDHEIM, OF ELIZABETH, NEW JERSEY, ASSIGNOR TO UNDERWOOD ELLIOTT FISHER COMPANY, OF NEW YORK, N. Y., A CORPORATION OF DELAWARE.

TYPEWRITING MACHINE.

Application filed September 5, 1924 Serial No. 736,028.

This invention relates to "billing" typewriting machines of which the standard Underwood is an example.

The object is to provide a simple, efficient and inexpensive mechanism for typing upon a work-sheet and tally-sheet or web singly or collectively.

One of the work-sheets is usually a bill or statement, and the other a web or tally-sheet. It is intended that the bill (or check) shall be initially typed upon through the medium of the vibratory main ink-ribbon at intervals corresponding to a definite number of line-spacings of the tally-strip with respect to the bill, to duplicate these typed impressions upon the tally-sheet or strip, so that a copy of the data typed upon the bill will be made only on certain lines of the tally-strip, together with similar lines of typed information copied from typed impressions made on other bills, and so on. In this manner a plurality of bills may be successively positioned in the paper-carriage and line-fed each in turn, as often as it is necessary, whereupon typewriting may proceed upon the bills only while these bills overlie the tally-strip on the platen, and in a manner, so that the tally-strip will not receive copies of certain of the lines typed upon the bill.

In the present invention, instead of carbon-sheets an auxiliary ink-ribbon is employed, and the billing machine is reorganized, so as to provide for the operation of the auxiliary ink-ribbon simultaneously with the mechanism for line-spacing the tally-strip, so that while the auxiliary ink-ribbon is being shifted relatively to the printing line of the machine, the tally-strip is also line-spaced relatively to the inert platen, and independently of the outer bill upon the platen, the outer bill having been typed through the main ink-ribbon, before the shifting of the auxiliary ribbon to its non-printing position.

The present invention provides a means for line-spacing the tally-strip at a point above the platen and in such a manner that just as soon as the tally-strip has been line-spaced the typing action can commence to type both the bill and the tally-strip.

A swinging frame supports the auxiliary ink-ribbon, and is manually-controlled so as to be shifted vertically. The frame shifts downwardly to position the auxiliary ink-ribbon at the printing line, and upwardly

to position this same ribbon near the printing line. Downward movement of the frame automatically feeds the auxiliary ink-ribbon. The tally-strip is also automatically line-spaced, slipping around the platen intermittently, the action being such that the auxiliary ink-ribbon moves downwardly towards the printing line, while the tally-strip is caused to move upwardly away from the printing line incidental to being line-spaced.

The auxiliary ribbon is guided circumferentially of the platen and supported at the printing line, and is not carried around with the platen when it is reversely rotated, and when this ribbon is shifted it will not tend to exert a backward pressure against the work-sheets or disarrange them.

Other features and advantages will herein-after appear.

In the accompanying drawings,

Figure 1 is a front elevation of the present invention.

Figure 2 is a top plan view thereof.

Figure 3 is a vertical sectional elevation thereof.

Figure 4 is an end elevation thereof, partly in section.

Figure 5 is a fragmentary detail view of a platen and ribbon-guide mounted thereover.

Figure 6 is a view similar to Figure 5, but showing the ribbon in shifted position.

In the drawings which are merely illustrative of the invention, 10 designates the usual type-bars carrying the type-surfaces 11 which move operatively so as to impinge upon the main ink-ribbon 11^a which vibrates in the printing zone of the machine in the usual manner, and which also serves to transfer typed impressions onto an auxiliary ribbon to be hereinafter described. 12 designates the platen which is rotatably mounted on a shaft 13 having its bearings in a platen-frame designated broadly 18, the usual pressure feed-rolls 14 and 15 being provided for holding the work-sheets under tension, and in engagement with the underside of the platen 12, which is disposed adjacent an apron 16 forming a part of a paper-shelf 17.

19 designates an auxiliary ink-ribbon which serves as a manifolding agent in transferring, at stated intervals, typed impressions from the type-surfaces 11 to one of several work-sheets held in the platen,

preferably the tally-strip A, the other worksheet B being in the nature of a bill or check typed upon directly through the medium of the main ink-ribbon 11^a.

5 The auxiliary ink-ribbon 19 is disposed for travel in a horizontal plane, so as to extend longitudinally of the platen 12, as shown in Figure 1, and is arranged to have its ends movably project through the oppositely-inclined and diagonal slots 21 formed upon suitable guide-plates 20 which have upper extensions 22 and 23 suitably secured upon a swing-frame about to be described. After passing through the slots 21 the adjacent parts of the auxiliary ribbon 19 pass upwardly and at right angles to the longitudinal stretch of said ribbon extending adjacent the platen, and are trained upon feed-spools 26 which are operatively mounted 10 upon trunnions 25 having their bearings in the extensions 23 of the guide-plates 20, friction being exerted against the rotation of these spools by means preferably of brakes 32 pressed against the sides of these 15 spools by means of thumb-pieces 33. 31 designates supports located at the opposite ends of the platen-frame, and mounted thereupon are brackets 30. Arranged to rotate with each spool 26 is a ratchet-wheel 20 34 which is engageable intermittently by one of two suitable feed-paws 35, these pawls being mounted one upon a pin 36 secured upon a lever-handle 37 having a finger-engaging piece 38^b; the other pawl 35 is secured operatively upon a sleeve 74 surrounding the shaft 29. This handle 37 is mounted upon the rock-shaft 29 and also operatively mounted upon this rock-shaft 29, in a manner to be actuated by the lever-handle 37, are the end plates 23 of a swinging frame to which frames are secured the guide-plates 20 and the spools 26 hereinbefore described.

45 The feed-paws 35 are held in engagement with the ratchet-wheel 34 by means of retractable springs 35^a secured at one point to the pawls, and at another point being fixedly mounted upon the swinging end plates 23, by which means said pawls are yieldably held in engagement with the ratchet-wheels. A cam-member 90 is formed in the shape of a crank, and is secured through fasteners 37^b to a collar 37^c, this member being provided with upper and lower cam-recesses 38 and 39, respectively, in either of which is removably located, a roller 40 secured upon a crank 40^a. The lever-handle 37 has a projecting lug providing a pin 41 which slidably projects in a segmental slot 43 formed upon one of the end plates, a retractable spring 44 being secured upon the pin 41 at one end, and to a pin 44^a fixedly secured to the end-plate 23, this spring normally holding the pin 41 at the upper end of the segmental slot 43. It will be seen

that the end-plates 23 are cut away to provide a recess 75, so as to provide clearance between the swing-frame and the platen-shaft 13. Also connected operatively to the lever 37 is a feed-pawl 46 extending upwardly, arranged to intermittently actuate a ratchet-wheel 48 fastened upon a shaft 49, having its ends journaled in a mid-frame consisting of side members 69 and 70, which mid-frame is pivotally positioned upon the rock-shaft 29, and is supported also upon the platen 12 by means of rollers 71 secured to said side members 69 and 70, the rollers 71 rotatably engaging the platen, as shown clearly in Figure 3.

Also fixed upon the counter-shaft 49 is a gear 50 meshing with another gear of the same size designated 51, which serves as a means for rotating a take-up roll 52, operatively mounted upon a counter-frame 85 consisting of side members 61 which counter-frame is operatively supported upon the mid-frame in the following manner.

The mid-frame consisting of the side members 69 and 70, is formed with journal recesses 85 which removably receive the ends of a shaft 55 upon which is fast a gear 98, the shaft 55 holding a feed-roll 58, this feed-roll constituting a source of supply of the tally-strip A. The side members 61 are pivoted upon the shaft 49, and are also provided with notch portions 62 removably fitted around so as to be supported upon the ends of the shaft 55, as is clearly shown in Figure 3. In this manner the side members 61 are operatively supported in position with respect to the mid-frame, the object being to permit the counter-frame consisting of the side members 61 to be raised sufficiently to permit the removal of the shaft 55 out of the journal recesses 85, made to receive the same so as to replenish this shaft with a fresh roll of the tally-strip.

It will be understood that the tally-strip is arranged to be moved toward and beyond the printing line of the platen progressively, so as to be line-spaced between the typing intervals line by line. The tally-strip preferably extends downwardly from the feed-roll 58 and is trained around the bottom of the platen 12, so as to be able to slip relatively thereto without imparting rotation to the platen. The tally-strip then extends upwardly of the platen, and is carried over to the take-up roll 52, which is operated in time with the feed-roll through the gearing hereinbefore described. A retractable spring 77 is secured at one end to a pin 79 on a lug 79^a formed upon one of the side members 61, the other end engaging a pin 78 on the feed-pawl 46 to hold it in engagement with the ratchet-wheel 48. A slidible push-rod 94 extends between the side members 61, and stretched thereover is the tally-strip A as it leaves the platen, and is taken up

by the take-up roll 52. A tearing-off knife 65 is also connected to the side members 61 by means of fasteners 66, shown in Figure 3, and is located above the platen 12.

It is necessary and desirable to provide suitable tension against the unrolling or unwinding of the tally-strip A from the feed-roll 58 in order that the tally-strip may be effectively fed for line-spacing purposes by means independent of the platen, so that it may be actuated to accomplish its function at the time that the auxiliary ribbon 19 is being positioned so as to be located at the printing line of the machine, so there is provided a counter-shaft 86 journaled in the side members 61 and having operatively secured thereon a sleeve 86^a in which is mounted a spring-brake or tension spring 86^a, which brake is effective to resist the unwinding of the feed-roll under normal conditions, that is to say, when the feed-roll has not become unduly enlarged in its diameter; in the latter instance the brake 86^a is overcome, but owing to the large diameter of the roll 58 the friction and tension exerted against the end of this roll and against the weight thereof by the coil-spring or brake 67 surrounding the shaft 49 (as shown in Figure 1), is increased the moment the tension of the spring or brake 86^a is unable to provide sufficient tension against the unwinding of the roll 58. This makes a slip brake, the spring 67 also engaging a fixed collar 68 secured upon the shaft 49. Therefore as the tally-strip is being continuously unwound from the roll 58 the gear 98 which rotates in unison therewith is tensioned by means of its meshing relationship with gear 91 on the shaft 86, and it follows that the take-up roll 52, which is mounted on the hollow shaft 53 and upon which the several convolutions of the tally-strip are wound to gradually increase the diameter of the roll, cannot accomplish its take-up action upon the tally-strip except against the tension of the brakes 86^a and 67, for as fast as the take-up roll 52 turns in a clockwise direction the feed-rolls turn in a counter-clockwise direction. The effect of the brakes 86^a and 67 is to assure that during each intermediate actuation of the ratchet-wheel 48, the tally-strip A is line-spaced a distance of say one line at all times.

In order to hold the mid-frame against displacement from the rock-shaft 29 the side members 69 and 70 thereof are provided with segmental portions 83 which overlie the top of the sleeve 74 surrounding said rock-shaft, the hook-shaped members 76 extending around the sleeve 74 at a point below the segmental portions 83 to assure the proper bearing of these segmental portions, thereon, these hook-shaped members being secured at 82 upon the side members 69 and 70.

A detent 63 engages the ratchet-wheel 48

to prevent the retrograde movement thereof step by step in the usual manner, being pressed into engagement with said ratchet-wheel by means of the usual leaf-spring 64. The spring-brake 86^a is caused to rest at one end against a collar 88 secured on the shaft 86, as shown in Figure 2. In order to properly position the auxiliary ink-ribbon 19 and support the same at printing-line position relatively to the platen, and especially to prevent this ribbon being carried along with the platen as it is being reversely rotated, special guide-members are provided in the shape of segmental members 102 formed with the preferably segmental or arcuate slots 103, these members being secured upon a bar 99 which extends longitudinally of the platen, so as to have its opposite ends secured upon the side members 69 and 70 of the mid-frame. The auxiliary ribbon 19 movably projects in the slots 103 of the guide-members 102, the bearing of the latter being sufficiently close to the printing surface of the platen to assure that the ribbon will be in close proximity to the printing line and this ribbon is movable to a position near the printing line as it moves circumferentially of the platen to this position. It will be seen that it does not move vertically, and therefore will not have a tendency to push backwardly the work-sheet B, which is usually a bill or check, so as to disturb the relative arrangement of this work-sheet in contact with the platen in a manner which will be well understood by those skilled in the art. Figure 6 shows the stretches 19^a of the ink-ribbon 19 offset at the point where the ribbon, after having been moved away from the printing line, projects beyond the guide-members 102, over around the guide-plates 20 in the diagonal slots 21. The ribbon movably projects through and beyond these slots, so as to be diverted in direction of movement from a horizontal to a vertical plane.

The operation of the present invention is as follows. In the first place the swinging frame supporting the auxiliary ink-ribbon and the ribbon-feeding spools form the subject matter of an independent application, so that the parts responsible for the operation thereof have not been shown or illustrated in great detail. However, it will suffice to state that when the lever-handle 37 is depressed a short distance this action results in the pin 41 riding along the segmental slot 43 formed in the end-plate 23 of the swing-frame which movement of the lever-handle takes place relatively to the cam 90 which does not move in unison with the lever-handle at this time. The pin 41 moves against the tension of the retractable spring 44, and during this movement the feed-paws 35, one of which is shown at 46,

are actuated by the lever-handle 37 to intermittently advance the ratchet-wheel 34 a distance of one tooth, whereby the spools 26 are rotated in opposite directions to feed 5 and take up respectively the auxiliary ink-ribbon 19, so as to bring a fresh surface thereof against the printing line. Finally the pin 41 reaches the end of its movement in the segmental slot 43 while the lever-handle 37 is still being pushed downwardly, and this time the swinging frame consisting of the end-plates 23, is also depressed. As the end-plates 23 swing down they turn the rock-shaft 29 which lifts the cam 90, so 10 that the roller 40 becomes positioned in the cam recess 39, shown in Figure 4, at which time the auxiliary ink-ribbon 19 has been moved in the segmental slots 103 of the guide-members 102, downwardly, so as to be 15 located at the printing line. The roller 40 will then hold the swinging frame locked with the auxiliary ribbon at the printing line.

Just as soon as the feed-pawls 35 are actuated during the depression of the lever-handle 37 the other feed-pawl 46 is simultaneously actuated to advance the ratchet-wheel 48 a distance of one tooth by virtue of which the gear 50 rotates and causes the gear 51 25 to rotate, the latter being fast on the hollow shaft 53 which carries the take-up roll 52, thereby causing this roll to wind up the tally-strip A, preferably a distance of a single line-space, as explained, against the tension 30 of the spring-brakes 86^a and 67. It will thus be seen that the auxiliary ink-ribbon 19 is lowered in one direction, so as to be positioned at the printing line while the tally-strip is being advanced in an opposite direction, so as to be line-spaced. Now it will 35 readily be seen that the main ink ribbon 11^a will be in alignment, during the typing action, with the auxiliary ribbon 19, and owing to the fact that the tally-strip overlies the platen, the auxiliary ink-ribbon 19 will be interleaved between this tally-strip and the work-sheet (whether bill or check), which overlies this ribbon, this auxiliary ribbon having the main ribbon 11^a engaging the 40 same during the typing action. Therefore any lines typed upon the bill or check produce typed impressions simultaneously upon this bill and the tally-strip which latter serves as the means for permanently recording 45 the data thus typed seriatum. Now should it be desirable to insert a new bill or check and to type one or more lines thereon without recording the same on the tally-strip, the typist takes hold of the finger-piece 38' of the handle-lever 37 and raises the same, so as to lift the swing-frame consisting of the end plates 23 to the position shown in Figure 4, during which action the feed-pawls are withdrawn or retracted from 50 their respective ratchet-wheels, and during

which action also, the auxiliary ink-ribbon follows the curvature of the segmental slots 103 of the guide-members 102, and is moved to a position near the printing line without disturbing the contacting relationship between the tally-strip and the work-sheet. During this action the take-up roll and feed-rolls remain idle or inactive, and inasmuch as the auxiliary ink-ribbon is disposed above the printing line, it follows that only the 70 bill or work-sheet B will receive typed impressions through the medium of the main ink ribbon 11^a. Thereafter, when it is desired to reproduce typed impressions upon the tally-strip for recording purposes it is 75 assured that the typed lines thus reproduced will not coincide with lines already typed upon the tally-strip at the time that the auxiliary ink-ribbon is again brought back to the printing line in a manner hereinbefore explained, because just before the ink ribbon reaches its printing-line position the tally-strip has been line-spaced automatically. 80

It will be appreciated that the present invention provides a simple contrivance that will efficiently line-space the tally-strip at the same time that the auxiliary ink-ribbon is being positioned at the printing line, and that the platen 12 can be rotated for line-spacing purposes in the usual manner, but as it rotates it will only serve to line-space the bill or outer work-sheet B, so that it will slip relatively to the tally-strip A which is trained thereupon under tension, and will be ineffective to line-space the tally-strip. If it is desired to lower the auxiliary ink-ribbon 19 to locate it at the printing line without line-spacing it at the same time, this can be done by the typist taking hold of the handle 97 of the lever 96 and turning the same 90 around to cause a cam 95 on the lever 96 to engage the push rod 94 which is attached to the gear 50, so as to cause this gear 50 to slide the sleeve 92, upon which this gear is mounted against the tension of the spring 95 67, shown in Figure 2, which action moves the gear 50 laterally and out of mesh with the gear 51, so as not to rotate the take-up roll 52. 100

Variations may be resorted to within the 105 scope of the invention, and portions of the improvements may be used without others.

Having thus described my invention, I claim:

1. In a typewriting machine, the combination with a platen having a work-web engaging therearound, of an auxiliary ribbon positioned thereadjacent, means for supporting said auxiliary ribbon, manually-controlled means for lowering said supporting means to position said ribbon at the printing line of the platen, and means automatically operated during the lowering of said supporting means for line-spacing said web. 120

2. In a typewriting machine, the combination 125

nation with a revoluble platen around which a work-web may be held, of an auxiliary ribbon, means for supporting said auxiliary ribbon above the printing line, means for lowering said supporting means to position said ribbon at the printing line of the platen, means controlled by the last-named means for line-spacing said web, and means for tensioning the movement of said web during its line-spacing action.

3. In a typewriting machine, the combination of a platen-frame, a platen revolubly mounted therein and around which a work-sheet extends, types, an auxiliary ribbon disposed at the printing line of said platen, a main ribbon producing typed impressions upon said work-sheet, said platen also having a tally-strip engaging therearound and underlying said work-sheet, manually-controlled means for moving said auxiliary ribbon to and from printing-line position, said tally-strip receiving impressions of said types through said auxiliary ink-ribbon, and means operated by said manually-controlled 25 means for automatically line-spacing said tally-strip.

4. In a typewriting machine, the combination of a rotatable platen around which a work-sheet is held, means whereby said platen may line-space said work-sheet, said platen also having a tally-strip held in engagement therewith and underlying said work-sheet, means engaging said tally-strip for line-spacing it independently of said platen, a main ink-ribbon for typing said work-sheet, an auxiliary ink-ribbon underlying said main ribbon for typing said tally-strip, and means acting in time with the last-named means for moving said auxiliary ribbon away from the printing-line circumferentially of the platen.

5. In a typewriting machine, the combination of a rotatable platen having a tally-strip trained thereupon and a work-sheet overlying said tally-strip, a source of supply for said tally-strip, a handle actuatable independently of said platen for advancing said tally-strip from its source of supply around said platen, means for maintaining a substantially uniform tension on said tally-strip at all times as it is advanced, two ink ribbons for simultaneously producing typed impressions upon said work-sheet and said tally-strip, and means for causing only said work-sheet to receive typed impressions.

6. In a typewriting machine, the combination with a platen, a rock-shaft above said platen and parallel thereto, a swinging frame, and an auxiliary ribbon having its ends supported on opposite ends of said frame and extending therefrom lengthwise of said platen and being moved to the printing line by swinging said frame to its down position, of a carrier frame supported on said rock-shaft and said platen, a feed-roll

for a tally-strip mounted on said carrier frame for rotation against friction, an upper frame superposed on said carrier frame, a take-up roll for said tally-strip mounted in said upper frame for rotation against friction, and mechanism operable upon downward movement of said swinging frame and arranged for rotating said take-up roll to line-space said tally-strip around said platen.

7. In a typewriting machine, the combination of a rotatable platen having a work-sheet fed therearound and a tally-strip underlying said work-sheet, types a main ribbon operatively transferring typed impressions upon said work-sheet, an auxiliary ink-ribbon, and manually-controlled mechanism for moving said auxiliary ink-ribbon circumferentially in one direction to position it in alignment with the main ribbon to receive impressions from action of said types and to transfer the same onto a tally-strip, said mechanism moving said tally-strip in an opposite direction to the movement of said auxiliary ribbon and simultaneously with the latter.

8. In a typewriting machine, the combination of a revoluble platen, line-spacing mechanism for rotating the platen around which a work-sheet may be fed along when the platen rotates during its line-spacing action, said platen also having a tally-strip arranged therearound to be moved underneath said work-sheet against said platen to and beyond the printing line thereof, means for moving said tally-strip, a main ribbon transferring typed impressions upon said work-sheet, and a length of auxiliary ribbon controlled by said means and disposed to be moved circumferentially with respect to said platen and in unison with the tally-strip into a position where it aligns with the main ribbon so that it may transfer typed impressions onto the tally-strip.

9. In a typewriting machine, the combination of a rotatable platen having a tally-strip trained thereupon, means for tensioning said platen to allow said tally-strip to slip therearound, a take-up roll engaging one end of said tally-strip, a feed-roll engaging the other end of said tally-strip, means for simultaneously actuating the feed and take-up rolls, and an auxiliary ink-ribbon actuated by the last-named means and positioned thereby at the printing line of the platen.

10. In a typewriting machine, the combination of a rotatable platen having a tally-strip trained therearound, means tensioning said tally-strip upon said platen, an auxiliary ink-ribbon positioned above the printing line of the platen, mechanism for causing said tally-strip to slip relatively to said platen, means moving with said mechanism for positioning said auxiliary ribbon at the printing line of the platen, and manually-

controlled means for actuating said tally-strip slipping mechanism.

11. In a typewriting machine, the combination of a platen-frame, a platen rotatably mounted therein, a ribbon-guide circumferential with respect to said platen and positioned at each end thereof, a swinging frame movable relatively to said platen-frame and locatable at and near the printing line of said platen, means for yieldably holding said swinging frame in either of its mentioned positions, an auxiliary ink-ribbon mounted upon said swinging frame and passing through said ribbon-guides, a tally-strip being engaged with said platen, means for line-spacing said tally-strip relatively to the printing line of said platen, said line-spacing means being mounted upon said swinging frame, and means operable upon the moving of said swinging frame to printing-line position for actuating the line-spacing means of said tally-strip.

12. In a typewriting machine, the combination of a platen-frame, a platen rotatably mounted therein, a ribbon-guide circumferential with respect to said platen and positioned at each end thereof, an auxiliary ink-ribbon disposed in said ribbon-guides, a frame supporting said ink-ribbon, means for raising and lowering said ribbon-frame, said ribbon-frame when lowered positioning said ribbon at the printing line of the platen, means operable upon the lowering of said ribbon-frame for feeding said ink-ribbon along the printing line, and means also operable upon lowering of said ribbon-frame for line-spacing a work-sheet.

13. In a typewriting machine, the combination of a platen rotatable therein, an auxiliary ink-ribbon, a swinging frame supporting said ink-ribbon, manually-controlled means for raising and lowering said swinging frame, said swinging frame when lowered positioning said ink-ribbon at the printing line of said platen, a tally-strip trained upon said platen, means for tensioning said tally-strip against said platen, and means operable automatically upon the lowering of said swinging frame for allowing said strip to slip relatively to said tensioning means and platen for line-spacing purposes.

14. In a typewriting machine, the combination with a platen, a rock-shaft above said platen and parallel thereto, a swinging frame fast on said rock-shaft, and an auxiliary ribbon having its ends supported on opposite ends of said frame, said ribbon being moved to the printing line by swinging said frame to its down position, of a carrier frame supported on said rock-shaft and said platen, a feed-roll for a tally-strip mounted for rotation against spring-brake friction on said carrier frame, an upper frame superposed on said carrier frame, a take-up roll for said tally-strip mounted in said

upper frame for rotation against spring-brake friction, a knife mounted on said upper frame for severing said tally-strip, and a pawl-and-ratchet actuating mechanism operable upon downward movement of said swinging frame and arranged for rotating said take-up roll to line-space said tally-strip around said platen and to feed said auxiliary ribbon lengthwise of said platen.

15. In a typewriting machine, the combination of a platen-frame, a platen rotatably mounted therein, manifolding means above the printing line of said platen and suitable for receiving typed impressions and transferring the same onto a work-sheet held against said platen, means for moving said manifolding means circumferentially with respect to said platen to locate it at the printing line of the platen, and manually-controlled means for line-spacing said work-sheet just prior to locating the manifolding means thereat.

16. In a typewriting machine, the combination of a rotatable platen, a swinging frame, an auxiliary ink-ribbon extending across said swinging frame at the front of said platen, said swinging frame being normally held above said platen so as to position said ribbon above the printing line thereof, a counter-frame movable upon the swinging frame, a feed-roll mounted between said swinging frame and counter-frame off which a tally-strip is fed to be wound around said platen, a take-up roll mounted in the counter-frame for line-spacing the tally-strip, means on said swinging frame for actuating the take up means, and means for tensioning the unwinding of said tally-strip from said feed-roll.

17. In a typewriting machine, the combination of a platen-frame, a platen rotatably mounted therein, a rock-shaft in back of said platen, a frame swinging with said rock-shaft to a lowered position, an ink ribbon mounted upon said swinging frame and positioned at the printing line of said platen when said swinging frame is lowered, a handle for manually lowering said swinging frame, means engaging a tally-strip for feeding it above said platen intermittently, means engaging the tally-strip for tensioning it as it is fed, and means controlled by said swinging frame as it is lowered for actuating said feeding means.

18. In a typewriting machine, the combination of a rotatable platen, a rock-shaft permanently mounted thereabove, a swinging frame fast on said rock-shaft, an auxiliary ribbon on said swinging frame, means for feeding along said ribbon, manually-controlled means for lowering said swinging frame to position the ribbon at the printing line of the platen, means controlled by the manual means for actuating the ribbon-feeding means, and means controlled by the last

named means for feeding a tally-strip above said platen and relatively thereto.

19. In a typewriting machine, the combination with a platen and a length of auxiliary ribbon extending longitudinally of said platen, of means for positioning said ribbon in typing position, overlying the leading end of a tally-sheet adjacent the printing line of said platen, said means including a bail pivoted in the rear of said printing line and having an arm member positioned at each end of said platen, mechanism for latching said arm members in position for supporting said ribbon a short distance above said printing line in a position so that said tally-sheet may pass between said ribbon and said platen, a handle arranged for unlatching said arm members and swinging them counterclockwise, and devices for guiding said ribbon circumferentially of said platen to the printing line thereof.

20. In a typewriting machine, the combination of a rotatable platen, an auxiliary ribbon, a frame supporting said ribbon, a tally-strip being trained around said platen, a feed-roll from which said strip is unwound, a frame supporting said feed-roll and engaging the other frame, a take-up roll upon which said strip is wound, a frame supporting said take-up roll and engaging the second-named frame, manually-controlled means for intermittently moving said ribbon to locate it at the printing line of the platen, and means for simultaneously feeding said ribbon along the printing line and actuating said feed and take-up rolls to line-space said strip above the printing line.

21. In a typewriting machine, the combination of a platen-frame, a platen rotatably mounted therein, a ribbon-positioning device mounted above said platen, a tally-strip being engaged with the platen at the printing line thereof, a feed-roll for said strip movably supported on said device, a frame swinging upon said device and raisable to permit the removal of said feed-roll, a take-up roll on said swinging frame, and means for actuating said feed-roll and take-up roll simultaneously with the ribbon-positioning device.

22. In a typewriting machine, the combination of a platen-frame, a platen rotatably mounted therein, a ribbon-positioning device over said platen, a feed-roll, a shaft upon which said feed-roll is fixed, a frame supported above said device, said shaft being movably mounted in said last-named frame, a counter-frame pivoted upon the second-named frame and movably supported upon said shaft, a tally-strip being extended from said feed-roll around said platen, a take-up roll in said pivotal frame receiving the free end of said tally-strip, and means on said device manually-operated to move said feed and take-up rolls for line-spacing said tally-strip.

23. In a device of the kind described, the combination of a platen-frame, a platen mounted therein, a rock-shaft in back of said platen, a frame fastened upon said rock-shaft, a ribbon on said frame, means for holding said frame to position the ribbon above the printing line of said platen, a mid-frame having side members pivotally supported upon said rock-shaft, rollers carried by said side members engaging said platen to support said mid-frame thereon, a tally-strip being trained around said platen, a feed-roll movably mounted in said mid-frame and receiving one end of said tally-strip, a top frame having side members pivoted upon the mid-frame and having portions movably resting upon the mid-frame, and a take-up roll journaled in the top frame and receiving the other end of said tally-strip.

24. In a typewriting machine, the combination of a platen-frame, a platen rotatably mounted therein, a frame supported above said platen, a tearing-off knife extending longitudinally of said platen and supported upon said frame, a work-sheet being held against said platen and presentable against said knife for severing action thereagainst, a tally-strip being trained in slipping relation around said platen and having one stretch extending thereabove toward said tearing-off knife, a take-up roll in said frame receiving the mentioned stretch of said strip, manifolding means for transferring typed impressions upon said tally-strip, means on said frame for intermittently rotating said take-up roll to line-space said strip, and means for manually rotating said platen relatively to said strip to line-space said work-sheet.

25. In a typewriting machine, the combination of a frame, a tally-strip being moved therewith, means for stretching said tally-strip in movement, a work-sheet being moved relatively to and in contact with said tally-strip, means at one end of said frame for feeding and actuating said work-sheet, means at the opposite end of said frame for feeding said strip relatively to said work-sheet, a ribbon transferring typed impressions upon said work-sheet, a second ribbon adjacent said tally-strip, and manually-controlled means for bringing the two ribbons together for simultaneously transferring typed impressions upon said work-sheet and tally-strip.

26. In a typewriting machine, the combination of a rotatable platen, a frame swinging relatively thereto, an ink-ribbon moved by said frame to locate it at the printing line of the platen, a tally-strip being engaged around said platen, means for successively moving sections of said strip past said printing line, gearing for operating said means, and means controlled in move-

ment by said swinging frame for actuating rotatably said gearing.

27. In a typewriting machine, the combination of a rotatable platen, an auxiliary ink-ribbon, means normally positioning said ribbon above the printing line of said platen, means for moving said ribbon longitudinally of said platen, means for shifting said ribbon to locate it at the printing line, a tally-
10 strip being positioned for movement relatively to said platen about the printing line thereof, means for pulling said strip to line-space it, gearing for operating the last-named means, a ratchet for intermittently
15 operating said gearing, and means for simultaneously bringing said ribbon to the printing line and actuating said ratchet.

28. In a device of the kind described, the combination of a rotatable platen, a rock-
20 shaft disposed rearwardly thereof, a ribbon-positioning frame movable with said rock-shaft, a frame having side members, segmental collars on said side members supported upon said rock-shaft, hook-shaped
25 members on said side members engaging said rock-shaft to hold said segmental collars against displacement therefrom, rollers carried by said side members engaging said platen to support the last-named frame
30 thereupon, a work-sheet being held against said platen, means above said second frame for line-spacing said work-sheet, means on the second frame for operating said line-spacing means intermittently, and manually-
35 controlled means on said ribbon-positioning frame for actuating said operating means.

29. In a typewriting machine, the combination of a rotatable platen, an ink-ribbon extending longitudinally thereof in printing
40 line position, spools located at the ends of said platen, upon which the ends of said ribbon are trained for feeding purposes, means for moving said ribbon circumferentially of said platen and away from printing-line position, means for manually-returning said ribbon circumferentially of said platen to printing-line position, and means
45 operated simultaneously with the last-named means for feeding said ribbon longitudinally of said platen.

30. In a typewriting machine, the combination of a rotatable platen, spools rotatably journaled adjacent the ends thereof, an ink-ribbon trained upon said spools,
50 means for disposing the intermediate stretch of said ribbon for horizontal travel longitudinally of said platen, means for rotating said spools to feed said ribbon, a depressible handle for intermittently operating said
55 spools, a work-sheet being trained around said platen and moving independently

thereof, and means controlled by said handle when depressed for simultaneously shifting said ribbon circumferentially of said platen toward the printing line and moving said work-sheet forward around said platen. 65

31. In a typewriting machine, the combination of a frame, a platen rotatably mounted therein and having a work-sheet disposed therearound, spools located adjacent the ends of said platen, a ribbon extending longitudinally of said platen and trained upon said spools, ratchet-mechanism for intermittently rotating said spools and work-sheet, means tensioning said work-sheet against said platen, means above said platen for line-spacing said work-sheet, ratchet-mechanism for intermittently operating the last-named means, manually-controlled means for shifting said ribbon towards and from the printing line of the 80
platen, and means controlled by the ribbon-shifting means for simultaneously actuating the two ratchet-mechanisms. 75

32. In a typewriting machine, the combination of a rotatable platen, a horizontal shaft upon which said platen is mounted, horizontal shafts adjacent the end of said platen, spools journaled upon said last-named shafts above said platen, arcuate members positioned between the ends of said platen and said spools and having arcuate slots, a ribbon having a stretch extending longitudinally of said platen and having its ends projecting through said slots above the printing line of the platen and trained upon 90
said spools, and manually-controlled means for shifting said spools and causing said ribbon to move in said slots to be located at the printing line of the platen. 95

33. In a typewriting machine, the combination of a rotatable platen, spools rotatably mounted adjacent the ends of said platen, a frame supporting said spools, guide-members depending from said frame adjacent the ends of said platen, said guide-members having arcuate slots disposed in proximity to the circumferential surface of said platen, a horizontal-disposed ribbon having its ends movably projecting there-through, so as to be guided in said arcuate 100
slots, means controlled by said spools for moving said ribbon longitudinally of said platen and beyond said guide-members, and guide-plates supported upon said frame in line with and in front of said spools and having slots through which said ribbon movably projects in the direction of said spools so as to space the horizontal stretch of said ribbon from the slots in said guide-members. 105
